UNITED STATES PATENT OFFICE.

ARTHUR J. STRONG, OF DETROIT, MICHIGAN.

AUTOMATIC SCREW-MACHINE.

1,187,563.

Specification of Letters Patent. Patented June 20, 1916.

Application filed July 12, 1913. Serial No. 778,654.

To all whom it may concern:

Be it known that I, ARTHUR J. STRONG, residing at Detroit, in the county of Wayne and State of Michigan, have invented certain new and useful Improvements in Automatic Screw-Machines, of which the following is a full, clear, and exact description.

The invention which constitutes the subject matter of this application relates to an automatic machine for constructing small articles, such as set-screws, double screws, binding posts and the like, the principal object consisting in devising improved means for automatically performing in one and the same machine, not only the preliminary, but subsequent operations upon suitable stock to produce a finished article.

The scheme of making screws by means of a horizontal turret carrying a series of tools to be presented in succession is old, but I am not aware of any machines of this character that are provided with novel mechanism comprising interconnected rotatable turrets and capable of automatically performing subsequent operations, where required, to make the finished product.

My invention, therefore, briefly consists in a machine for performing successive operations upon a blank stock to produce finished articles, and comprises a plurality of successive blank holders in connection with means for transferring blanks from one holder to the succeeding holder, and means for performing one or more operations upon the blank while it is maintained in each of the holders, one of said holders and one of the means for effecting operations upon the blank consisting of interconnected rotatable turrets adapted to be rotated and moved longitudinally in unison. In conjunction with a machine of this character I also employ a means, such as a punch, for performing certain characteristic or desired operations other than those usually performed by the tools of turrets.

Other objects, advantages and characteristics of my invention will appear from the detail description taken in connection with the accompanying drawings, in which—

Figure 1 is a side elevation of a machine embodying this invention. Fig. 2 is a sectional view taken through the working space of Fig. 1, and looking toward the turret mechanism of the machine. Fig. 3 is a sectional view taken on the same line as in Fig.

2, but looking in the opposite direction. Fig. 4 is an end elevation of Fig. 1. Fig. 5 is an elevation of the end opposite to that shown in Fig. 4. Fig. 6 is a plan of Fig. 1. Fig. 7 is a section through the machine 60 showing the transferring-device mechanism. Fig. 8 is a detail of the arrangement, used in this embodiment to operate the turrets of the same. Figs. 9, 10, 11, 12, 13 and 14 show the evolution of a set-screw during the various steps in the process of making it with this machine, and referring more particularly to the figures: Fig. 9 shows the stock as fed through the machine, Fig. 10 shows the stock in section after it has been centered 65 by means of the second tool of the tool-carrying turret, Fig. 11 shows the stock in section, after it is drilled by the third tool of said turret, Fig. 12, the next step, shows the blank cut off the stock and beveled and 70 key-fitted by the punch, Fig. 13 shows the blank after it has been acted upon by the tool in spindle 45, namely, end-cupped, Fig. 14 shows the blank after it has been externally threaded, which is the last step. 75

Referring to the drawings in detail, the reference character 1 indicates suitable stock which may be in the form of a bar of solid or hollow cross section, or may be in the form of blanks of suitable size, and 80 is disposed in a horizontal rotatable sleeve or spindle 2, which preferably extends from one end of the machine to a suitable working space, where it terminates in a rotating head 3 and is provided with suitable 85 journals 4. The rotating head is provided with the necessary mechanism for properly retaining the stock in place. The stock is of a size to permit its free passage through the sleeve, and the only mechanical connection between it and the sleeve is made by 90 means of the clutch mechanism 5. This clutch mechanism is fixed to, and rotates with, the sleeve 2, but is capable of longitudinal movement thereon. When, however, 95 the clutch is moved forward, that is, in the direction of the head 3, it clamps the stock and pulls it forward too, and at the same time rotates with it. When the clutch device is moved backward it releases the stock and slides over it into its former position to be ready to clutch the stock and move it forwardly a predetermined distance. The mechanism in the head 3 provides sufficient resistance to prevent the stock from 100 105 110

being retracted when the clutch mechanism is retrieved to its first position. To move the clutch mechanism backward and forward I employ a ship 6 which is provided with a bifurcated arm 7 engaging the grooved portion 8 of the clutch mechanism, and a toe or pin 9, which is automatically actuated by the force bars 10 on the drum 11, located adjacent thereto. The spindle and associated mechanism is of the usual construction.

Rigidly mounted on the spindle 2 is a pulley 12, which receives power from any suitable source and thereby rotates the sleeve. A spur gear 13 is also secured to the sleeve and through intermediate gearing operates a gear 14 mounted on a shaft 15, thereby imparting a continuous motion to the worm 16. This worm wheel meshes with and actuates the worm wheel 17, fixed to one end of a horizontal shaft 18, the other end of which is also provided with a worm wheel 19, meshing with a worm wheel 20, fixed upon one end of a shaft 22 arranged longitudinally of the machine. To this shaft 22 is secured the drums 21 and 11 and cam wheels 23 and 24.

A frame 25 serves to hold the parts of the machine, as is clearly shown in the drawings.

On the drum 21 are force-bars or cams 26 which are arranged so as to periodically reciprocate a toe or pin 27, which in its movement causes a carriage 28 to slide with it in special grooves 29 provided for it in the frame.

The carriage 28 is provided with a pair of turrets 30 and 31, which are suitably geared together, one of which is provided with holders to contain various tools to operate on the blanks, while the other is provided with means for holding the blanks for subsequent treatment. When the carriage is moved forward one of the tools in the tool-carrying turret is alined with stock, and if properly arranged will act on the same, owing to the rotation of the stock. As the carriage is brought back to its rearward position it brings a clutch mechanism 32 into play so that the shaft 15 will cause a sleeve shaft and gear 33, movable with the carriage, to be operated, and this in turn, through a chain transmission 34, rotates the special mechanism 35 which causes each turret to turn around a predetermined amount and thus present a different tool for the stock or blank.

In the construction shown, the tool-carrying turret 31 is provided with three tools *a*, *b*, *c*, and the carriage 28 is brought back and forth, as above described, until all the tools have acted upon the stock, after which the blank is in condition to be severed from the stock (if the latter be in the form of continuous bars) and to be transferred to a

second holder for subsequent treatment by other tools.

The mechanism for cutting the blank from the bar stock consists of a lever 36 operated by the cam 23 and connected to the carriage 37, which is provided with a suitable cutter 38. The cam effects a reciprocation of the carriage 37, in the path of the cutter of which is located the stock, and this reciprocation of the cutter severs the blank from the stock.

The cam wheel 24 is provided for the purpose of operating the mechanism for transferring the blank from one holding station to the other, and consists of a segmental lever 39 actuated by said cam, a segmental member 40 which meshes with the toothed segment on lever 39, and an arm 42. The segment 40 and arm 42 are fixed to a common shaft 41 so that an oscillation of the segment 40 will impart a corresponding movement to the arm 42. This arm is provided with a resilient catch 43 for engaging and securely holding the blanks. The positions to which it is desired to transfer the blanks by the specific mechanism shown is controlled by the shape of the periphery of the cam, which is so constructed that it transfers the blank to a plurality of stations at one or more of which the arm is given a period of dwell, whereby certain characteristic operations are effected without the blank being necessarily removed from the transfer arm. For instance, it is necessary in many operations of this character to use a punch, such as I have diagrammatically indicated at 44. In this case, it is not necessary to remove the blank from the transfer arm, it being sufficient to bring the blank into the field of action of the punch and to maintain the same in such position for a period commensurate with the time required for effecting the punching operation. This operation makes the hole in the blank of hexagonal, rectangular, fluted, or any other desired form of tightening with a similarly shaped wrench; also for holding in the succeeding operations of pointing and threading.

The means for pointing the blank is indicated at 45, while the means for threading the same is indicated at 46, the latter consisting of a die holding member in which a suitable die is placed. The former is preferably operated left hand from sleeve 2, by means of gears 3 and 49 for pointing the blank, while the latter is operated right hand from the same source through the intermeshing gears 47 and 48 for threading. These pointing and threading means are located in front of the turret 30, and when the latter is rotated to the proper positions the blank on the holder will be in exact alinement with the pointing and threading means.

The general operation of the machine will now be described, and the further coöperation of the parts explained.

The first act of the machine, after the 5 same has been started, will be to feed the stock forward by means of the clutch device into engagement with the stop *a* of the tool-carrying turret which defines the length of the blank to be made. Upon the rearward 10 movement of the carriage a clutch 32 comes into action and brings the centering tool of the said turret into alinement with the stock, and a forward movement of the carriage, caused by one of the force bars or 15 cams 26 coming into contact with the part 27, will disengage the clutch 32 at this point and cause the centering tool *b* in turret 31 to act on the rotating stock 1. The carriage will then be forced to retract by 20 virtue of one of the cams 26, and because of the reengagement of the clutch 32 the turret will be caused to take up another position in which the succeeding tool, that is, the drill *c*, and the blank will be in alinement. 25 The carriage then being brought forward, the drill will then operate upon the stock and retreat as before, thus causing another reengagement of the clutch. It will thus be seen that the operation continues until 30 the blank has been treated by the required number of tools in the tool holding turret. As soon as the turret has made one complete rotation, the cam wheel 24 will act on the lever 39 and the transfer arm will be so operated 35 as to have its finger mechanism 43 catch on to the stock. The cam wheel 23 will then act on its lever 36, and the cutter will cut the blank off, which will then be in the finger mechanism of the transfer arm. The next 40 swing of the transfer arm will bring the blank under the punch and the squared hole in the back will be made in the blank. The next swing of the arm will bring the blank immediately in front of the blank holder 45 (which is shaped to correspond to the hole in the blank) of the second turret 30, and in its timed movement forward the holder will engage the squared hole of the blank and as the carriage retreats the transfer arm will 50 leave the blank on said holder. While the carriage 28 is in its forward position, to which it has been moved to cause the blank holder on the turret 30 to engage with the blank held in its path by the transerrer, the 55 stock rod is fed forward to the stop *a* for another blank. The carriage 28 is then withdrawn, carrying the blank on the holder. This movement, as before explained, causes an engagement of the clutch 60 32, which indexes the turrets one position, placing the centering tool *b* of turret 31 in line with the stock rod, and the blank holder on turret 30 in line with the tool spindle 45 for cupping the point of the blank. Consequently when the carriage is advanced, as

previously explained, the tool on spindle 45 cups or points the blank held by the turret 30, while at the same time the succeeding blank is being operated upon by means of the centering tool *b* in turret 31. The carriage is again withdrawn and the turrets indexed another position, which brings the next tool *c* on the tool-carrying turret into alinement with the stock for drilling the same, and the blank on the other turret into 75 alinement with the spindle 46, which carries the die for threading the blank and which is driven at a reduced speed from the spindle, 2.

The die spindle 46 does not reverse as is 80 common with devices of this character, but is moved constantly in one direction, the blank being forced through the die spindle by the succeeding blanks and drops from the same completely finished.

It is very obvious that the tools employed in the tool-carrying turrets and in the spindles may be varied in number and kind, and while I have indicated in the drawings and described the use of three tools on the tool-carrying turret and two tools on the two spindles opposite the holding turret, it will be understood that this is for illustrative purposes only. Some of these tools may be dispensed with, other substituted therefor, or 95 the number used may be increased without deviating from the invention.

The turrets are geared together, to run either in the same or opposite directions, and are operated through a gear actuated by a 100 shaft connected with the mechanism 35. The punch is tripped by a simple arrangement which the transfer arm acts upon as it brings the blank into position to be operated upon by the said punch. The clutch 5 may be of 105 any usual type suitable for the purpose, being such that it will tighten on the stock when moved in one direction, and release the same when moved in the opposite direction. This clutch may be of the type 110 shown and described in the patent to Hawkesell *et al.*, #551119.

While but one modification of the invention has been described in the specification, it is not intended to limit the invention to that 115 particular construction, or in any other way, otherwise than limited by the prior art, as many modifications in the construction of the invention may be made without deviating from the principles thereof and still 120 come within the scope of the appended claims.

What I claim is:—

1. In a device of the class described, a rotating head adapted to hold stock, a plurality of turrets, one of said turrets having a plurality of tools adapted to operate upon the stock, a second turret having a work holding means mounted thereon, a rotating spindle adjacent to the head of the machine 130

and in a position to carry the stock into co-operation with the tools on the first mentioned turret, a second spindle provided with a tool, means to transfer a blank from the rotating head to the work holding means on the turret, where it can be acted upon by the said tool, and means for effecting a relative movement of the turret and the tools and spindles, whereby a plurality of operations may take place substantially simultaneously.

2. In a device of the class described, a plurality of spindles, one of said spindles adapted to rotate stock, and the other provided with a cutter, a pair of parallel turrets, one of said turrets having tools mounted thereon to act upon said stock, the other turret having work holding means adapted to secure a blank and present the same to said cutter, and transferring means adapted to remove a blank from the first mentioned spindle and transfer the same to the work holding means on the second turret, and means for effecting a relative movement of the turrets and spindles.

3. In a device of the class described, a plurality of rotating spindles, one of said spindles being adapted to hold stock, a second of said spindles having a rotating cutting means secured thereto, a plurality of turrets, one of said turrets having tools mounted thereon to operate upon the stock, the second of said turrets having a work holding device, a cut-off tool adapted to cut off the stock upon the completion of the operations of the tools in the first turret, means adapted to grip the blank before it is cut from the stock and transfer said blank after it is cut off to the work holding means in the second turret, and means for effecting a relative movement of the turrets and spindles whereby a plurality of cutting operations may take place simultaneously.

4. In a device of the class described, comprising, in combination, a plurality of turrets disposed substantially in the same plane, means for periodically changing their relations, one of said turrets provided with operating means, means for rotating stock in position to coöperate with the operating means on said turret, the second turret provided with blank holding means, a cutting means in alinement with blank holding means on the second turret, means for bringing the turrets into closer relation with the cutting means and the stock rotating means, and means for transferring stock from position in front of the first turret to the holding means on the second turret.

60 5. A machine of the class described, comprising, a plurality of turrets, a blank rotating means in front of one of said turrets, and a rotating die in front of the other turret, the second mentioned turret provided

with means for holding a blank, and the 65 first mentioned turret provided with means for operating upon the succeeding blank in the rotating means, in combination with a punch, and means for transferring the successive blanks from the blank rotating means 70 first to the punch and then to the blank holding means on the second turret.

6. In a device of the class described, comprising, in combination, means to rotate a blank, a plurality of turrets, one of said 75 turrets having a plurality of tools adapted to be presented successively to operate upon the blank, a punch, a work holding means in the other turret, and a transferring means adapted to first transfer a blank from its 80 holder to the punch and then transfer the blank to the work holding means in the second turret, and means for operating upon said blank as the same is held by the second turret.

7. In a device of the class described, in combination, means to rotate a blank, a plurality of turrets, one of said turrets having a plurality of tools adapted to operate on said blank, a second turret having a work 90 holding means thereon, a punch adapted to broach the blank upon the completion of the operations thereon of the tools of the first turret, means to transfer the blank from the blank rotating means to the punch, said 95 means being adapted to transfer the blank from the punch to the work holding means on the second turret after the broaching operation has been completed, and means for operating upon said blank as the same is 100 held by said second turret.

8. In a machine of the class described, in combination, a plurality of turrets, one of said turrets adapted to effect a preliminary operation upon the blank, the other turret 105 having a work holding means thereon, a punch and a means to transfer a blank from its first position, where it undergoes the preliminary operation, successively to the punch and to the work holding means in the second 110 turret, the time of said last mentioned means having a period of dwell during which a broaching operation is effected upon the blank in the punch, and means for operating upon said blank as the same is held by the 115 second turret.

9. In a device of the class described, a rotating head adapted to hold a blank, a plurality of interconnected rotatable turrets, one of said turrets provided with means for operating upon the blank held by the rotatable head and the second turret having means adapted to hold another blank, mechanism located adjacent to the rotatable head for operating upon the blank on the holding means of the second turret, means for advancing and retracting the turrets to and from said rotatable head and said mecha- 125

nism, whereby the respective blanks are operated upon by the operating means, and means for transferring successive blanks from the rotating head to the said holding 5 means on the second turret.

10. In a device of the class described, a rotating head adapted to hold a blank, a rotatable holder mounted adjacent to said rotating head, in combination with a plurality 10 of interconnected rotatable turrets, one of which is provided with tools adapted to be brought into alinement with the blank and the other of which is provided with a blank holder in substantial alinement with the die, 15 means for transferring a blank from the rotating head to said holder after it has been operated upon by said tools, and means for simultaneously advancing and retracting the turrets to and from the rotating head 20 and die holder whereby a plurality of operations are simultaneously effected.

11. A machine for automatically operating upon a blank to produce a finished article, comprising a spindle for intermittently 25 feeding stock to a predetermined point, in combination with a plurality of interconnected rotatable turrets operated in unison, one of said turrets provided with means adapted to operate upon said blanks in the 30 spindle and the second turret having a work holding device to receive the blank from said spindle, means for transferring the blank from the spindle to said work holder, and means for operating upon said blank 35 while retained by the work holder of the second turret to finish the same.

12. In a device of the class described, a rotating head adapted to hold a blank, a plurality of interconnected rotatable turrets, 40 one of which is provided with tools adapted to be brought into alinement with the blank, and the other of which is provided with a holder for said blank after the latter has been operated upon by the tools in the first 45 turret, rotatable cutting means mounted adjacent to said rotating head and located in substantial alinement with said holder on the second turret, means for transferring a blank from the rotating head to said holder, 50 and means for advancing and retracting the turrets to and from the rotating head and cutting means whereby a plurality of operations are simultaneously effected.

13. In a device of the class described, a 55 rotating spindle adapted to hold stock, a rotatable die holder mounted adjacent to said rotating head, in combination with a plurality of interconnected rotatable turrets, one of which is provided with tools adapted 60 to operate upon the blank before the same is severed from the stock, and the second of which is provided with a blank holder adapted to be brought into alinement with the die, means for severing the blank from

the die after the same has been operated 65 upon by the said tools, mechanism adapted to engage said blank before the same has been severed from the stock and transfer the same after severance to the holder on said second turret, and means for simultaneously 70 advancing and retracting the turrets to and from the rotating head and die holder whereby a plurality of operations are simultaneously effected.

14. A machine for automatically presenting 75 blanks to successive working tools to produce a finished article, comprising a plurality of stations for holding blanks while the same are acted upon by various tools, in combination with means for operating upon 80 the blanks while the same are held in the aforesaid stations, one of said stations and one of the tool-carrying means comprising interconnected rotatable turrets operating in unison, and means for transferring successive 85 blanks from one holding station to the other.

15. A machine for performing successive operations upon a blank to produce finished 90 articles, comprising a plurality of successive blank holders, in combination with means for transferring the blanks from one holder to the succeeding holder, and means arranged in juxtaposition to each of said 95 holders for performing one or more operations upon the blanks, one of said holding means and one of the tool-carrying means comprising interconnected turrets adapted to be rotated and reciprocated in unison with each other.

16. A machine for performing successive operations upon a blank to produce finished articles, comprising a plurality of interconnected 100 rotatable turrets operated in unison with each other in combination with a plurality of spindles located in alinement with said turrets, means for transferring stock from one of said spindles to one of said turrets after it has been preliminarily treated by the tools of the other turret, and means 105 for advancing and retracting the turrets toward and from said spindles whereby a plurality of operations take place at the same time.

17. A machine for performing successive 110 operations upon a blank to produce finished articles, comprising a plurality of interconnected rotatable turrets, one of said turrets having means thereon for operating upon a blank and the other turret provided with 115 means for holding the preceding blank, in combination with a plurality of rotatable spindles, one of which is adapted to hold the stock while it is operated upon by the tools of the tool-carrying turret and the 120 others of which are adapted to operate upon the blank held by the other turret, means for 125 transferring blanks from the stock holding
